COMBINATION CAN COVER AND DISPENSER FOR LIQUIDS

Lillian M. Baker, Miami Beach, Fla.

Application December 24, 1948, Serial No. 150,349

Term of patent 3½ years

(Cl. D58—17)

To all whom it may concern:

Be it known that I, Lillian M. Baker, a citizen of the United States, residing at Miami Beach, in the county of Dade and State of Florida, have invented a new, original, and ornamental Design for Combination Can Covers and Dispensers for Liquids, of which the following is a specification, reference being had to the accompanying drawing, forming a part thereof.

In the said drawing:

Figure 1 is a side elevational view of a combination can cover and dispenser for liquids, showing my new design;

Fig. 2 is a top plan view thereof;

Fig. 3 is a front elevational view thereof; and
Fig. 4 is a bottom plan view thereof.

I claim:

The ornamental design for a combination can cover and dispenser for liquids, as shown.

LILLIAN M. BAKER.
